Primary Examiner — Celia Murphy*Assistant Examiner* — Kathleen M Sims(74) *Attorney, Agent, or Firm* — Guy McClung(57) **CLAIM**

The ornamental design for pocket for connection to folder, as shown and described.

DESCRIPTION

FIG. 1 is a front view illustrating my design for a pocket for connection to folder;

FIG. 2 is a rear view thereof;

FIG. 3 is a side view thereof;

FIG. 4 is a side view thereof;

FIG. 5 is a top view thereof; and,

FIG. 6 is a bottom view thereof.
